UNITED STATES PATENT OFFICE.

CARLEY GOULD WELD, OF NORTH CHATHAM, MASSACHUSETTS.

CARBURETER.

1,014,682.

Specification of Letters Patent.

Patented Jan. 16, 1912.

Application filed October 14, 1910. Serial No. 587,028.

To all whom it may concern:

Be it known that I, CARLEY GOULD WELD, a citizen of the United States, residing in North Chatham, in the county of Barnstable and Commonwealth of Massachusetts, have invented certain new and useful Improvements in Carbureters, of which the following is a full, clear, and exact specification.

10 This invention relates to carbureters and has among its objects the supplying of an explosive mixture of constant richness to an internal combustion engine with a given relative adjustment of the parts, irrespective of variations in the quantity of the explosive mixture required by the engine; the supply of the components of the mixture being subject to independent relative adjustment for adjustably proportioning these 20 and predetermining the richness of the mixture.

The invention is particularly applicable for use in supplying a mixture of gasolene and air to a gasolene engine. The effective area of the opening of the air port is controlled by the strength of the suction from the engine cylinder, and the effective area of the opening of the gasolene port is controlled in unison with the air port but is 30 adjustable relative to the air port for varying the richness of the mixture supplied.

In one form of my invention, which may be regarded at present as the preferred form, and which is illustrated herein, the 35 registering openings for forming the air port are shown rectangular, the area of effective port opening being controlled by the suction from the engine cylinder; and a pair of ports, one rectangular and the other 40 triangular, one adjustable as to its own area, and one adjustable relative to the other, are shown for the gasolene, the effective area of this gasolene port being shown controlled in unison with the air port, and adjustable 45 relative thereto.

In the drawings accompanying and forming a part of this specification an illustrative example of a practicable embodiment of one form of my invention is shown, in 50 which,

Figure 1 is a central vertical section of the device. Fig. 2 is an elevation of one of the parts detached. Fig. 3 is an elevation of the lower portion of the parts shown 55 in Fig. 2 looking at this from the right hand side. Fig. 4 is a section taken on a

plane at about the line 3—3 of Fig. 1 and at about right angles to the plane of Fig. 1, and Fig. 5 is a detail of the valve-forming parts, showing the valve in its open position.

The following is a detailed description of the illustrated form of my invention:

There is provided a gasolene float tank 5, which is adapted to be secured to some suitable part of the engine or to its support. It has a gasolene pipe. A two-diameter cylinder is illustrated; the portion of larger diameter 7, is provided at one end with a flange 8, for securing to the engine. This portion is also provided with a throttle 9. The other end of the larger portion is provided with a flange 10, which constitutes a closure for the float chamber 5. The portion 11, which is the portion of lesser diameter of the cylinder, extends through the float chamber and is provided at its lower end with a screw thread, engaging a screw-threaded opening in the lower wall of such chamber, and is also provided with a lock-nut 12, for making a tight joint at this point. This screw-threaded connection holds the closure flange 10 down upon the float chamber. The portion 7 of the cylinder is provided with an inlet port 13, open 80 to the air. This port is located in such position that it will be closed by a piston mounted in the cylinder and opened by movement of such piston. The piston is a two-diameter piston having a two-diameter 90 chamber. The portion 14 of larger diameter has a working fit with the portion 7, of larger diameter of the cylinder, and is provided with a port 15 which, when the piston is at the end of its in-stroke, will be out 95 of register with the port 13. As the piston is sucked up by the engine drawing in its charge these ports will come into register one with the other.

It will be noted that the floor portion of the port 15 slants inwardly. This is for the purpose of collecting any ungasified gasolene and directing it inwardly to such position that the movement of the air will take it up. The outline of these ports is 105 rectangular and they are of substantially of the same dimensions and form. A slot 16 is made in the side of the piston portion 14 for the engagement of a stop 17 which will limit the inward and the outward excursions of the piston in its reciprocations. It is so timed that an amount of space 18 is

provided for acting as a cushion or dash pot on the inward excursion. The portion 19 of lesser diameter of the piston is in the form of a tube carried by the piston head 5 and is in the main free from engagement with the interior of the portion 11 of the cylinder. It is, however, provided at its lower portion with an enlargement 20 which will have a guided movement, but sufficiently 10 free to permit passage of air to and from the dash pot space 18.

An elbow tube 21 extends from the lower portion of the float chamber and carries a stand-pipe 22 which has a port 23 in connection with the elbow tube 21. The upper end of the stand-pipe extends into the piston portion 19 at its lower part. For the purpose of regulating the amount of opening at the upper end of the stand-pipe there 20 is provided a top or closure 24 carried by a stem 25 which extends within the stand-pipe and has at its lower end a screw-threaded connection at 26 with what may be termed the base portion 27 of the stand- 25 pipe, which portion by means of a set nut 28 and a flange 29 will be securely clamped in position. The lower portion of the stem 25, is provided with a screw driver connection and a key 30, whereby the stem may be 30 rotated and the screw thread connection rendered effective for raising and lowering the closure head 24, for making a larger or smaller annular outlet or port for the gasoline at the top of the stand-pipe. The portion 35 27 carries a stuffing box 270 for the stem of its key 30 for preventing leakage at this point. A sleeve 31 having a close fit with the stand-pipe and reciprocable relative thereto, is carried by the piston. The 40 sleeve is closed at its upper end which closure is in the form of a nut 32 which has screw threaded connection with a hanger 33 carried by a bracket 34 fast on the head of the piston. The lower portion of the 45 sleeve 31 is provided with a slot 35, which is engaged by a finger 350 of an actuator 36, whereby the sleeve may be rotated for effecting its longitudinal adjustment relative to the piston. The sleeve 31 is provided with a triangular port 37, the base 50 of which is about 240 degrees of the circumference of the sleeve 31. The port 37 is placed with its apex at its upper portion and is located in position to register with the 55 annular port 38 between the head 24 and the end of the stand-pipe 22 when the piston is drawn up.

By adjusting the head 24 relative to the 60 end of the stand-pipe 22 the lateral dimension of the port between the annular port 38 and the port 37 will be adjusted. The amount of movement of the sleeve 31 relative to the port 38 will control the effective area of opening at the port at each piston 65 movement. After the sleeve 31 and the head

24 have been adjusted the amount of opening of the gasoline port will be controlled by the amount of movement of the piston which controls the amount of opening of the air port. The strength of suction at the 70 piston will control the amount of its movement so that the air and gasoline supply will be always in a predetermined ratio after the parts have been adjusted. The mixture will be delivered in a quantity corresponding with requirements, and of uniform richness irrespective of the amount which is drawn from the carburetor at any time. The form of the port in the sleeve 31 will reduce the leakage of gasoline at 80 this point particularly at low speed, which leakage would have a tendency to make the gasoline too rich at the low speeds.

From the foregoing description it will be seen that the amount of gasoline delivered 85 may be regulated by regulation of the port 38 and that the timing of the opening of this port may be regulated by adjusting the longitudinal position of the sleeve 31.

As the sides of the port opening are 90 straight it will be seen that the increase in the amount of gasoline admitted is in direct proportion to the lift, and as the air ports are rectangular and the vacuum constant, it is evident that the air and gasoline 95 will always be in the same proportion. The amount of gasoline admitted for a definite amount of lift can be regulated by the height or vertical dimension of the annular port 38.

The initial air port is provided between the small diameter chamber part 19, and the sleeve 31. The vertical adjustment of the sleeve 31 gives the correct amount of gasoline for the air which comes through the 105 primary air opening, this being made small enough so that even at the lowest speeds the main air ports will come into use.

The foregoing is a detailed description of one form of embodiment of my invention 110 which has been found efficient in practice but it is to be understood that I do not purpose limiting myself to this exact construction since changes may be made within the scope of my invention.

Having thus described my invention what I claim and desire to secure by Letters Patent is:

1. In a carburetor the combination with a piston open to the suction of the engine cylinder, of a member having an air port located in position to be controlled by the piston, a member having a gasoline port located in position to be controlled by the piston, means for regulating the relative timing of these ports, and means independent thereof for adjusting the efficient area of opening of one of the ports relative to the other.

2. In a carburetor the combination with a 130

piston open to the suction of the engine cylinder, of a cylinder having an air port located in position to be opened and closed by the piston in its reciprocations, a member having a gasoline port located in position to be opened and closed by the piston in its reciprocations, means for regulating the timing of the opening and closing of these ports one relative to the other, and means independent of such regulating means for adjusting the efficient area of opening of the gasoline port relative to the air port.

3. In a carbureter the combination with a piston exposed to the suction of the engine cylinder, of a cylinder therefor having an air port located in position to be controlled by the movement of the piston, a member in communication with a source of gasoline supply, and provided with an adjustable annular gasoline port, and a member adjustably carried by the piston and provided with a triangular port located in position to register with the said annular port upon the piston movement.

25 4. In a carbureter the combination with a piston exposed to the suction of the engine cylinder, of a cylinder therefor having an air port located in position to be controlled by the movement of the piston, a source of gasoline supply, a stand-pipe in connection therewith, a top for the stand-pipe adjustable relative to the top thereof for affording an adjustable annular gasoline port at the top, a sleeve surrounding said stand-pipe and adjustably carried by the piston and provided with a triangular port located in position to register with the said annular port upon the piston movement.

5. In a carbureter the combination with a two-diameter piston having a two-diameter chamber and a two-diameter cylinder for the piston, these being provided at their portions of greater diameter with air ports located in position to be closed when the

piston is at the end of its inward stroke and 45 opened by registering upon the outward piston movement, of a stand-pipe extending within the piston chamber of lesser diameter and in connection with a source of gasoline supply, and a closed top sleeve carried by the 50 piston and surrounding the stand-pipe and provided with a port communicating with the piston chamber of lesser diameter and located in position to be closed by the stand-pipe in the inward position of the piston 55 and to form a port with the end of the stand-pipe on the outward movement of the piston.

6. In a carbureter the combination with a two-diameter piston having a two-diameter 60 chamber and a two-diameter cylinder for the piston, these being provided at their portions of greater diameter with rectangular air ports located in position to be closed when the piston is at the end of its inward 65 stroke and opened by registering upon the outward piston movement, of a stand-pipe extending within the piston chamber of lesser diameter and in connection with a source of gasoline supply, a top for the 70 stand-pipe for affording an annular port, and means for adjusting the top for regulating the port area, and a sleeve having a closed top carried by the piston and surrounding the stand-pipe and provided with 75 a triangular port communicating with the piston chamber of lesser diameter and located in position to be closed by the stand-pipe in the inward position of the piston and to form a port with the annular port on 80 the outward movement of the piston.

In witness whereof I have hereunto set my hand in the presence of two subscribing witnesses.

CARLEY GOULD WELD.
